CLAIM

The ornamental design for a business card holder, as shown and described.

DESCRIPTION

FIG. 1 is a front perspective view of a business card holder showing my new design, the writing instrument depicted by means of broken lines being shown for illustrative purposes only and forming no part of the claimed design;

FIG. 2 is a front elevational view thereof;

FIG. 3 is a rear elevational view thereof;

FIG. 4 is a left side elevational view thereof, the right side elevational view being a mirror image of the left side view;

FIG. 5 is a top plan view of the business card holder; and,

FIG. 6 is a bottom plan view thereof.

1 Claim, 4 Drawing Sheets
